UNITED STATES PATENT OFFICE.

EDWARD OTTEN, OF BROOKLYN, NEW YORK.

MEANS FOR CONDITIONING INKING ROLLS.

Application filed October 17, 1924. Serial No. 744,137.

To all whom it may concern:

Be it known that I, EDWARD OTTEN, a citizen of the United States, and a resident of Brooklyn, county of Kings, city and State of New York, have invented certain new and useful Improvements in Means for Conditioning Inking Rolls, of which the following is a specification.

This invention relates to means for conditioning inking rolls and has for its primary object to provide an apparatus which is of relatively simple construction and which may be readily installed in operative position relative to a multiple type newspaper printing press whereby the inking rolls may be maintained at approximately the desired temperature so as to prevent undue softening of the rolls in summer or undue hardening of said rolls in winter.

In one practical embodiment of the invention, I illustrate the provision of means for projecting a plurality of streams of air under pressure transversely through or across the press adjacent to the inking rolls. In summer this air is cool, while in winter it is warmed or heated. Thus the air streams impinging upon the surfaces of the inking rolls will maintain the same in a substantially constant predetermined plastic condition so as to insure the proper inking of the type cylinders, while at the same time obviating the practical destruction of said rolls by melting of the ink composition, or on the other hand, hardening of the roll surfaces to such an extent that the type will not be properly inked.

The apparatus above referred to includes a plurality of flexible discharge conduits, and it is one of the important objects of the invention to provide an improved connecting means between these conduits and a common air supply header whereby the conduits may be independently moved or adjusted to various angular positions relative to the header for the purpose of permitting unobstructed access to different parts of the press.

With the above and other objects in view, the invention consists in the improved conditioning apparatus for inking rolls, and in the form, construction and relative arrangement of the several parts as will be herein-after more fully described, illustrated in the accompanying drawings and subsequently incorporated in the subjoined claim.

In the drawings wherein I have illustrated a simple and practical embodiment of

my present improvements and in which similar reference characters designate corresponding parts throughout the several views:

Figure 1 is a side elevation partly in section, showing a preferred embodiment of the invention and diagrammatically illustrating its application in relation to two newspaper printing presses;

Figure 2 is an enlarged fragmentary longitudinal section through the air receiving header; and

Figure 3 is a transverse section taken on the line 3—3 of Figure 2.

Referring in detail to the drawings, and more particularly to Figure 1 thereof, 5 designates two printing presses which may be of any familiar type or construction, each of said presses having one or more printing cylinders 6 and a series of inking rolls associated with each of said cylinders, as indicated at 7. These inking rolls are composed of a suitable composition material which initially is of a plastic nature, which is suitably hardened so as to provide a rigid body of cylindrical form. This cylindrical body or roll is provided at its ends with suitable means whereby it may be operatively mounted in the press in relation to the printing cylinder.

Up to the advent of the present invention, considerable loss of time in the operation of the presses as well as financial loss has been occasioned by the softening of these inking rolls so that they break down, necessitating the stopping of the presses and the replacement of the rolls by new ones. It will be understood that this trouble is particularly pronounced during very hot weather, owing to the high temperature in the press room. However, it is also a well known fact that when the reverse of such condition obtains during the winter when the press room is below a certain temperature, the surfaces of the inking rolls become hardened to such an extent that there is an inadequate supply of ink to the printing cylinders. I propose to remedy both of these conditions by means of my present invention.

For purposes of illustration, I have selected a form of the invention which has been applied and thoroughly tested with great success, but it is understood that the embodiment shown in the drawings is merely suggestive, and strict adherence to the arrangement of the pipe, the form of the

headers and the number of air discharge conduits is not required, but may be altered in numerous particulars, as the exigencies of each particular case may necessitate.

5 As herein shown, the main air supply pipe 8 is suitably mounted and supported adjacent the ceiling of the room, the diameter and capacity of this pipe being determined by the number of presses in connection with 10 which the apparatus is to be used. One end of the pipe 8 is open and extends through the building wall as shown at 9 for the entrance thereto of relatively cool external air. This open end of the pipe may be covered 15 by a sheet of wire or other reticulated material, indicated at 10, to prevent the entrance of leaves, stones, or other foreign matters to the interior of said pipe. Adjacent to this 20 end of the pipe a fan or blower 11 of any suitable type, is arranged therein and driven from a motor by means of the belt or other driving connection indicated at 12. At the inner side of this blower an opening is provided in one side of the pipe 8 normally 25 closed by the door 13 and through this opening a suitable electric heater may be inserted within the pipe so as to warm the incoming air when required.

At spaced points, substantially in line with 30 the presses 5, a branch pipe 14 of relatively small diameter extends downwardly from the main air supply pipe 8, the lower end of each branch pipe being connected with an inverted hollow or tubular Y shaped member 35 15, the spaced arms of which are connected as shown at 17 in Figure 2 of the drawings, to the upwardly extending nipples on opposite ends of the cylindrical header 16. With 40 this header a series of flexible metallic air discharge conduits 18 are connected in the manner to be presently explained in detail.

45 The flexible conduits 18 may be bent into any desired curved form so as to position their lower open ends adjacent the ends of the inking rolls 7 at one side of the press, as clearly shown in Figure 1 of the drawings, whereby a plurality of air streams will be delivered under pressure from the open ends of these conduits transversely across the 50 press and will impinge upon the surfaces of the inking rolls. It has been found in actual operation that in the absence of such cooling medium for the inking rolls when an unusually high temperature of the atmosphere 55 in the pressroom obtains, as in summer, the plastic composition material of which these inking rolls are composed will not maintain their rigid form but will sag, melt, bend or break down. They must then be removed 60 and replaced by new rolls. As these inking rolls cost from thirty-five to fifty dollars each, it will be apparent that such frequent replacement of the rolls is a considerable item of expense in the operation of the press. 65 When, in the winter, the atmosphere falls

below a certain temperature it becomes necessary to apply heat to the rolls so as to maintain the desired plastic condition of the surfaces thereof whereby the printing cylinders will be adequately inked. In such case 70 it is only necessary to insert the heater above referred to within the main air supply pipe 8 through the opening 13 so that the incoming air driven under pressure by the blower 11 through the pipe 8 will first 75 be heated before entering the header 16.

The cylindrical wall of each header 16 is provided in its lower portion with spaced circumferentially extending slots 19, and between these slots the annular metal bands 20 80 of less diameter than the header are arranged, suitable spacing rings 21 being interposed between said bands and the wall of the header and said bands and rings rigidly fixed to the header wall by rivets 22. It will 85 be noted that the spacing rings 21 are of appreciably less width than the band 20, thus providing annular spaces between said bands and the wall of the header. In these 90 spaces, the opposite ends of the sleeves 23 95 are loosely engaged for rotative movement. Each sleeve is provided with a radially extending nipple 24 projecting outwardly through one of the slots 19 in the header 100 wall. To these sleeve nipples the upper ends of the respective conduits 18 are suitably connected. By means of this construction, it will be evident, as indicated in Figure 2, that the several flexible conduits 18 may be readily swung in relation to the cylindrical 105 header independently of each other to various angular positions.

From the foregoing description considered in connection with the accompanying drawings, it is believed that the construction, manner of operation and several advantages of my present invention will be clearly and fully understood. While I have 110 illustrated the conditioning apparatus as applied to printing presses, it is apparent that such apparatus might be employed in connection with any other multiple arrangement of presses, it being merely necessary to provide a sufficient number of groups of 115 headers and air discharge conduits and to increase the capacity of the main air supply pipe in accordance therewith. Further, while I have shown one arrangement of the 120 air blower or fan and have described a construction of the air receiving headers which is quite desirable, it is to be understood that these and other features of my present disclosure are susceptible of embodiment in various other alternative structures, and I 125 accordingly reserve the privilege of adopting all such legitimate changes in the form, proportion and relative arrangement of the several parts as may be fairly embodied within the spirit and scope of the invention as claimed. 130

I claim:

In a conditioning apparatus for the inking rolls of a printing press, an air supply pipe, a cylindrical header, connections between the opposite ends of said header and the supply pipe, the wall of said cylinder having a plurality of circumferential slots therein, independently rotatable sleeves mounted in the header and having nipples projecting through the respective slots, a series of flexible conduits respectively connected at one of their ends with said nipples

and adapted to be independently adjusted to position their discharge ends adjacent to the inking rolls of the press, and means for delivering air under pressure to said supply pipe whereby air is discharged from said pipe in a plurality of streams transversely across the press contiguous to the inking rolls.

In testimony that I claim the foregoing as my invention, I have signed my name hereto.

EDWARD OTTEN.
